CLAIM

I claim the ornamental design for a lyra ring, as shown and described.

DESCRIPTION

FIG. 1 is a left perspective view of a lyra ring showing my new design in an assembled configuration;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a front cross-sectional view thereof, taken in the direction of line 8-8' of FIG. 5; and,

FIG. 9 is a left perspective view of the lyra ring of FIG. 1 shown in a disassembled and expanded configuration.

The broken lines showing of portions of the lyra ring depict environment and form no part of the claim.
